DISPLAY FORM

Nelson Hurwitz, Brooklyn, N. Y.

Application August 31, 1937, Serial No. 161,787

9 Claims. (Cl. 40—126)

This invention relates to forms simulating animate objects, and more particularly to forms of this character which are adjustable to various positions.

5 In display advertising, it has long been the practice to employ manikins or other similar forms for displaying the merchandise. Forms of this character are generally made of wax, plaster of Paris, and the like, and usually are of rigid construction. In cases where it has been found desirable to provide these forms with adjustable parts, such as the limbs of a human form, for example, the parts have been made movable by means of ball-and-socket or other similar joints, 10 all of which are limited in the manner of adjustment and, at best, can be adjusted only within definite limits. Moreover repeated operation of these joint connections eventually causes them to wear out, thus rendering the form unfit for further use unless repaired.

There are many articles of merchandise, particularly small items, which need be effectively displayed by only a portion of such forms. For example, a form simulating the human hand 15 may be employed to hold the article being advertised and thus bring it before the eyes of the purchasing public in an attractive manner. Obviously, since different articles of merchandise which may be so displayed vary in shape and 20 size over a wide range, it is necessary that the fingers of the form be made adjustable to accommodate a large variety of such articles. In some cases, also, it is highly desirable, if not almost imperative, that the fingers of the form be enabled 25 to grasp the article to be displayed in order to retain it in place properly, especially for a continued period. So far as I am aware, none of the forms heretofore in use have been constructed to serve effectively in this manner.

30 The primary object of my invention is to provide an improved form simulating an animate object parts of which may be readily adjusted to any desired position and which will remain in such position indefinitely when adjusted thereto.

35 More specifically, it is an object of my invention to provide an improved form simulating the human hand, the fingers of which may be readily adjusted to any desired position, which may be either natural and customary, or which may be 40 unusual.

Another object of my invention is to provide an improved form as aforesaid which is readily adjustable to grasp and retain an article of merchandise for display purposes.

45 Still another object of my invention is to pro-

vide an improved form simulating a human limb the digits of which may be adjusted to any grotesque or other unusual posture.

A further object of my invention is to provide an improved form of the type set forth the joints 5 of which are not subject to appreciable wear even after long continued use.

It is also an object of my invention to provide an improved form of the type described which may be suitably embodied in a toy as well as in a 10 display figure, which is simple, yet rugged, in construction and highly efficient in use, and which is inexpensive of manufacture.

In accordance with my invention, I make the display form or toy of a moldable material which 15 is flexible when it becomes set and mold it about a skeleton framework constructed of wire or the like. The wire framework is also flexible and preferably stiffer than the material of which the display form is made, but it is not resilient so that, 20 while it will readily yield to banding in any direction, it will not itself spring back to its original shape. Thus, the form may be adjusted to any desired position which it will thereafter retain.

In the case of a form simulating the human 25 hand, for example, the wire framework extends into the fingers whereby each finger may be bent or twisted at any point along its entire length and to any extent desired quite independently of any other finger. It will be seen, therefore, that 30 each of the fingers may be individually bent to some unusual and unnatural or grotesque shape, the form thereby attracting attention because it is so unusual. By bending the forefinger and as many of the other fingers as may be necessary 35 into suitable relation with the thumb, an article of merchandise can be readily grasped by the hand and held in place for display purposes, particularly where the wire framework is quite stiff. When applied to a toy, such as a doll, a bird, a 40 dog, or some other animal, the several parts thereof may be readily adjusted to, and will remain in, a number of positions dependent upon the ingenuity of the child to afford considerable amusement as well as to be of educational value. 45

The novel features that I consider characteristic of my invention are set forth with particularity in the appended claims. The invention itself, however, both as to its organization and method of operation, together with additional objects 50 and advantages thereof, will best be understood from the following description of several embodiments thereof, when read in connection with the accompanying drawing, in which

Figure 1 is a view, partly in section, of one form 55

of my invention as applied to a display form simulating the human hand,

Figure 2 is a similar view of a slight modification thereof,

5 Figure 3 is plan view of a modified form of skeleton framework constructed in accordance with my invention, and

Figure 4 is a view showing my invention applied to a bird.

10 Referring more particularly to the drawing, wherein similar reference characters designate corresponding parts throughout, there is shown, in Fig. 1, a display device 1 in the form of a human hand showing a suitably weighted supporting base 3 and including the five fingers 5, 7, 9, 11 and 13. The form 1 is molded of any suitable base material 15, such as suitably sized latex, synthetic resins, gelatinous substances, or the like, and which, when set, is flexible and preferably feels like human flesh to the touch. The base material 15 is molded around a skeleton framework 17 of non-resilient but flexible metal wire, such as lead, brass, copper, or the like, the wire 17 being entirely embedded in the base material 15 and being preferably stiffer than the latter. The skeleton framework 17 is originally shaped to represent the human hand and has portions thereof extending into each of the fingers through substantially the entire length thereof, 25 as more clearly shown in the modifications of my invention illustrated in Figs. 2 and 3. Preferably, the framework 17 is first dipped into the material of which the form is made and the coating thereon is allowed to dry and set, after which the coated framework is placed in the mold and the base material 15 is poured around it in well known manner, the molded hand being removed from the mold when the material 15 has set. The hand 1 may thereafter be covered, as by spraying, dipping, painting, etc., with a layer 19 which simulates human skin, and the fingers may be suitably finished with finger nails 21, if desired.

A hand simulating display device thus formed may be easily adjusted to suit various needs.

45 Since the wire 17 can be bent in any direction and extends substantially entirely through each of the fingers, it is obvious that the individual fingers may be bent or twisted at any desired points in their lengths as if provided with an infinite number of universal joints. This permits bending the individual fingers into unusual or grotesque postures. By way of illustration, the little finger 13 has been shown bent forwardly and downwardly, and twisted slightly toward the edge 23 of the 50 palm; the ring finger 11 has been shown bent backward and slightly toward the forefinger 7, as if it were double jointed; and the middle finger 9 has been shown bent forwardly about 90° and then twisted toward the little finger 13 to 55 assume a position in front of the rearwardly bent ring finger 11. Obviously, the fingers may be adjusted to many other positions in all of which they will be retained by the non-resilient wire framework 17 until adjusted to another position.

60 Within the range of universal adjustment permitted by the fingers of the display hand constructed according to my invention, it is also possible to bring the fingers and thumb into such relation that the articles of merchandise to be displayed thereby are firmly grasped and held up before the eyes of the purchasing public. For an illustration, I have shown the forefinger 7 and the thumb 5 adjusted to firmly grasp a cigarette 25. By selecting a relatively stiff wire for the framework 17 and bringing the forefinger 7 and the

thumb 5 into sufficiently close relation, considerable pressure will be applied to the cigarette 25, as seen from the depressed portion 27 thereof, whereby the cigarette or other article to be displayed will be held in place very firmly.

5 In the modification of my invention shown in Fig. 2, the hand 1 is shown holding a telephone receiver 31 in a natural posture, and the distribution of the skeleton wire framework 17 is shown in detail. In place of a solid wire framework, as 10 in Fig. 1, however, the framework 17 is made up of a multiplicity of individual strands twisted together into a single strand. A framework of this sort is preferable in some cases, since it lends itself more easily to twisting and bending.

15 In Fig. 3, I have shown a further modification of my invention wherein another type of framework is employed. A solid block of metal 41 may be bored to receive a plurality of wire or strip elements 43 of which those embedded in the fingers 20 have alternate sections 45 thereof flattened out while the remaining and shorter sections 47 of the elements 43 are retained in their original wire form. Preferably, the alternate sections 47 correspond to the knuckles of the human hand and 25 the flattened sections 45 extend between the knuckles. Since the sections 45 are wider than the sections 47, it will be obvious that they are stiffer transversely of the fingers, or in the plane of the paper, than are the sections 47. On the 30 other hand, in a plane normal to that of the paper, the flattened sections 45 are more flexible than the sections 47. Also, the relatively thin, wide sections 45 are much more easily subject to twisting, or to the influence of a torsional force 35 tending to distort them. This modification of my invention, therefore, enables many unusual adjustments not so easily possible with the frameworks previously described, and it will retain the fingers in any position of adjustment.

40 As heretofore indicated, my present invention is applicable not only to display devices, but to many other devices, such as toys. An example of a toy constructed according to my invention is the ostrich 51 shown in Fig. 4. The body, including 45 neck, tail and legs, may be molded as above described about a suitable framework 53. This construction permits bending or twisting the long neck of the ostrich to many different positions, and adjusting the legs thereof to sitting, standing, running, or any other posture, either natural or unnatural, as may be desired. In the case of other animals, such as an elephant, for example, the wire framework may be formed to extend through the trunk, tail and ears, as well as 50 the legs and neck, all these parts being rendered adjustable thereby in the manner heretofore described. Also, in the case of a human form, such as a doll or a display figure, it will be obvious that the framework may be arranged to extend 55 through the feet and toes as well as the hands and fingers, whereby all digits of each of the limbs of the body are rendered adjustable. Similarly, the framework may extend through the 60 arms, legs, ears, lips, nose, hips, trunk, and any other part of the body to produce unusual and interesting effects. Other changes, both in the materials of the base 15 and the frameworks 17 and 65 53, as well as in the structure and location of the framework will, no doubt, readily suggest themselves to those skilled in the art. I therefore desire that my invention shall not be limited except insofar as is made necessary by the prior art and by the spirit of the appended claims.

I claim as my invention:

1. In a figure simulating an animate object, the combination of a flexible base material formed to the shape of said object, and a skeleton framework representing said object embedded in said base material, said framework being made of a flexible material having greater stiffness than said base material and being non-resilient whereby it will retain the parts of said object in any position of adjustment, and said framework being formed at least in part of individual, unitary metal strips having alternate sections of relatively greater and lesser flexibility in a predetermined direction.
- 5 2. In a figure simulating an animate object, the combination of a flexible base material formed to the shape of said object, and a skeleton framework representing said object embedded in said base material, said framework being made of a flexible material having greater stiffness than said base material and being non-resilient whereby it will retain the parts of said object in any position of adjustment, and said framework being formed at least in part of metal strips having alternate sections of relatively greater and lesser flexibility in a predetermined plane, said sections of relatively greater flexibility in said plane being stiffer than the other alternate sections in a plane normal to said first named plane.
- 10 3. In a figure simulating an animate object, the combination of a flexible base material formed to the shape of said object, and a skeleton framework representing said object embedded in said base material, said framework being made of a flexible material having greater stiffness than said base material and being non-resilient whereby it will retain the parts of said object in any position of adjustment, and said framework being formed at least in part of individual, unitary metal strips having alternate sections which yield more easily under the influence of a torsional force than the remaining alternate sections thereof.
- 15 4. A display form simulating the human hand, said form being made of a flexible base material and including the five individual fingers, and a skeleton framework embedded in said base material, said framework being made of flexible metal
- having greater stiffness than said base material, and said framework having portions formed of alternate sections of relatively greater and lesser flexibility extending into each of the fingers throughout substantially the entire length thereof whereby said fingers may be individually bent anywhere along their lengths and in any desired direction, said framework being nonresilient and serving to retain said fingers in any position of adjustment.
- 5 5. A display form according to claim 4 characterized in that said framework is made of metal wire, and characterized further in that those portions of said wire which extend into the fingers are flattened at spaced points therealong whereby 10 to provide said alternate sections of relatively greater and lesser flexibility in a predetermined plane.
- 15 6. A display form according to claim 4 characterized in that said framework is made of metal wire, and characterized further in that those portions of said wire which extend into the fingers are flattened at spaced points therealong, said flattened portions being relatively stiff transversely of the fingers.
- 20 7. A display form according to claim 4 characterized in that said framework is made of metal wire, and characterized further in that those portions of said wire which extend into the fingers are flattened at spaced points therealong, said flattened portions being located at points intermediate the knuckles.
- 25 8. A display form according to claim 4 characterized in that said framework is made of metal wire, and characterized further in that those portions of said wire which extend into the fingers are flattened at spaced points therealong, said flattened portions being located at points intermediate the knuckles and being relatively stiff transversely of the fingers.
- 30 9. In a display form, a skeleton framework of nonresilient, flexible material, said skeleton being representative of said form and comprising a plurality of assembled, individual, unitary elements having alternate sections of relatively 35 greater and lesser flexibility.
- 40 45

NELSON HURWITZ.
